FACTORY FIRE-DRILL SYSTEM.

1,223,481.

Specification of Letters Patent.

Patented Apr. 24, 1917.

Original application filed February 25, 1914, Serial No. 820,950. Divided and this application filed June 7, 1915. Serial No. 32,543.

To all whom it may concern:

Be it known that I, DAVID G. DEE, a citizen of the United States, residing at Chicago, in the county of Cook and State of Illinois, have invented certain new and useful Improvements in Factory Fire-Drill Systems, of which the following is a full, clear, and exact description.

This invention relates to factory fire drill systems and is a division of the co-pending application filed Feb. 25, 1914, Serial Number 820,950, covering a similar invention.

The present invention has for its object to provide a system of electrical circuits and apparatus adapted to be used in conjunction therewith, and designed particularly for use in factories, schools and similar places wherein it is desirable to sound alarms in case of fire, and which may further be adapted for use in the conducting of fire drills required by law in many States and municipalities. The apparatus is further intended to be associated with a subscriber's telephone circuit leading to a central office or exchange whereby trouble of any kind, such as grounds, short circuits or breaks in the main alarm circuit, will be reported not only locally at the point of installations, but also at the central telephone office or exchange.

It is to be further understood that the present invention is also applicable not only for the purpose of sounding local fire alarms and transmitting trouble alarms to the central office, but also can be used in conjunction with apparatus for transmitting the fire alarm to the central office or exchange.

With the above and other objects in view, as will be apparent, this invention consists in the construction, combination and arrangements of parts and circuits all of which will be hereinafter more fully described, claimed and illustrated in the accompanying drawings wherein:

The figure is a diagrammatic illustration of a fire alarm circuit and apparatus therefor, constructed in accordance with the present invention.

Reference being had more particularly to the drawing, the present invention is illustrated in conjunction with a telephone subscriber's line circuit comprising the conductors 1 and 2 which, as is usual, extend to the central office or exchange, the latter being

equipped with the usual switchboard apparatus including, among other things, a subscriber's line or pilot lamp by means of which the operator is advised of an incoming signal, said lamp being lighted when the line circuit is closed and extinguished when the same is opened. The leading-in wires 55 which connect the subscriber's talking set to the line circuit or conductors 1 and 2 are indicated by 1^a and 2^a and it is across these wires that the combined alarm and drill system circuits are bridged.

An alarm system, such as the present invention, preferably comprises a series or plurality of fire alarm signal boxes designed primarily to despatch code signals over the alarm circuits. Two of these boxes are 70 illustrated in the accompanying drawings and indicated A and B. These signal boxes comprise code wheels driven in any suitable manner, such as a spring actuated clock train and which are normally prevented from operation by suitable restraining devices a—b coöperating with the escapement of the clock train. Electromagnets A' B' are provided with their respective restraining devices a—b whereby the 75 latter may release the escapement of the clock train when the electro-magnets A' B' are energized by closing their respective circuits either manually by push buttons or automatically by thermopiles or thermostats. 80 The circuits of these electro-magnets whereby the code or signal boxes are set in operation are exactly similar and each extends to a given locality in the building or series of buildings, each signal box A, B designating 85 a building or a portion of a building, as the case may be. For this purpose, viz. designating a portion of a building or a building in a series of buildings, the code wheel of each signal box is provided with a series of projections or teeth b' and b³ for the signal box B and a' and a³ for the signal box A. The first group of projections a' b' of each code wheel is designed to designate the portion of the building or the building in 100 which the fire is occurring; while the second group of projections a³ b³ is designed to indicate the exit to be used. That is to say, the projections or teeth a' designate that the fire is occurring on for instance the second 105 floor of a building while the second group of

projections or teeth a^3 indicates the exit to be used.

Coöperating with each code wheel A, B are the spring contacts a^2 , b^2 which are designed to be closed or brought together by the teeth or projections a' a^3 , b' b^3 , of the corresponding code wheels, it being apparent that when the circuit coöperating with each electro-magnet A' B' is closed, and the electro-magnet energized to attract the restraining devices a — b , the clock trains will be released for movement, rotating the code wheels A, B to make and break the circuit under the control of the contacts a^2 b^2 .

15 The alarm circuit, arranged to be closed by either the contacts a^2 b^2 , comprises the wires C and D, the first of which is connected to one side of a local battery X while the second wire forms a loop D' connected to one terminal of the relay coil E returning by way of the wire D² connected to the other terminal of the relay coil E, and terminating at the other pole of the battery X. This alarm loop has bridged thereacross, the alarm receiving mechanisms or bells F', F², F³, F⁴ and may be traced by the wire C, the battery X, the wire D², the relay coil E, the wire D' and the wire D. Inasmuch as the wires C and D which include the loop, terminate in the contacts a^2 b^2 , it is manifest that when said contacts are brought together, the loop circuit D' and D² is closed energizing the signal receiving devices or bells F', F², F³, F⁴ to correspond to the electric impulses in the circuit.

The loop circuit D' and D² is under continuous test so that any trouble condition arising thereon, whether a ground, a short-circuit, or a break, will be indicated and for this purpose a local trouble alarm G is provided in conjunction with the central office exchange or exchange indicator H. The local trouble alarm G constitutes a bell, a buzzer or other receiving mechanism located in the circuit g, g' which is supplied with the necessary current from the battery x'; said circuit being constantly open by the contacts g² and g³ on the relay E. Under normal conditions, as will hereinafter be apparent, the relay E is energized drawing up its armature thereby maintaining all contacts under the control of said armature open.

55 The central office trouble alarm or indicator H comprises an electro-magnet h, the coil of which is connected by the wires h' to the conductor 2^a and by the wire h² to the contact h⁴ of the armature of the relay E, said contact coöperating with a similar contact h³ which is connected by the wire h⁵ to the conductor 1 of the subscriber's line circuit. Thus, when the contacts h³ and h⁴ are brought together, the trouble signal H is bridged across the subscriber's line circuit,

the armature h⁶ of the electro-magnet h normally forming a continuation of the wire 2, 2^a by reason of its engagement with the back contact h⁷; and when the contacts h³ and h⁴ are brought together, the electro-magnet h is energized pulling up its armature which then engages the contact h⁸ connected with the wire h², whereby the magnet h is short circuited causing the armature h⁶ to fall away to again engage the contact h⁷, which operation continues as long as the contacts h³ and h⁴ are in engagement, thereby creating a continuous vibration which is noticeable upon the line or pilot lamp at the central office switchboard.

80 The armature of the relay E likewise carries two additional pairs of normally opened contacts (x³—x⁴ and y¹—y²) which, when closed, control the supply of current from the battery X to the two sides of the alarm loop as follows: Leading from one side of the battery X is the wire x² terminating in the contact spring x³ which when released engages the spring x⁴ which is tied to the wire D² by the wire x⁵. Leading from the other wire D' is a wire y connected to the contact spring y' which, when the armature of the relay E falls away engages the contact spring y², the latter being connected to the wire D' at the other end of the loop 95 by the wire y³. By the provision of these two pairs of contacts x³ and x⁴ and y' and y², the battery X is connected to both ends of the loop circuit so that in the event of the breaking of one or both of the conductors D' D², it will be possible to operate the receiving mechanisms or bells F', F², F³, F⁴ when one of the alarm box mechanisms A B is actuated or when the alarm circuit is manually closed for test or for fire 100 drill purposes.

In order that the signal receiving mechanisms or bells in the loop circuit may be operated primarily for fire alarm purposes or manually tested to indicate the condition 110 in operativeness, a pair of contacts h k² is provided, connected respectively by the wires h' h³ to the conductors C and D, said contacts being under the control of the key K. With the key K is further associated 115 two sets of normally closed contacts m and n, the former being interposed in the wire g' and the latter interposed in the wire h² said contacts serving to cut out the local trouble alarm and the central office trouble 120 indicator when the system is being tested for operativeness or being closed for the purpose of carrying out a fire drill. It is apparent that by closing the contacts h, h², the loop circuit is closed in the same manner 125 as the operation of the alarm despatching boxes A B.

The relay E being sensitive, is maintained energized by a slight current flowing from the battery X over the loop circuit so that 13

as long as the loop circuit remains intact and is not grounded, the armature of said relay will be pulled up maintaining the sets of contacts under the control thereof, open,

5 and in order that this may be accomplished, a high resistance winding E' is bridged across the conductors C and D, maintaining the loop circuit normally closed but permitting sufficient current to flow thereover 10 to maintain the relay energized, said current not being sufficient to operate the signal receiving mechanisms or bells $F' F^2 F^3 F^4$. The circuit thus formed when the loop circuit is closed is as follows:—

15 Battery X, conductor C, high resistance E' , conductors D D', the relay E, the conductor D^2 to battery. In the event of an alarm box A, B or the key K being operated, the resistance E' is short circuited creating 20 a current flow from the contacts a^2 , b^2 , or k k^2 through the conductor C, battery X conductors D^2 , relay E, conductor D', conductor D to the aforesaid contacts. Should 25 the loop circuit heretofore described be destroyed or broken, the dropping of the armature of the relay E causes its four sets of contacts to close and the two upper pairs of contacts g^2 g^3 and h^3 h^4 to complete the circuits which serve to indicate the conditions 30 of trouble locally and at the central office, respectively. The closing of the other two pairs of contact springs applies battery to both ends of the alarm loop so that in case of a break in the latter, the bells or signal 35 receiving devices $F' F^2 F^3 F^4$ may be operated notwithstanding this apparent interruption in the circuit.

To illustrate this, let the dots in the conductors D' D^2 represent a break in both of 40 said conductors in which event the closing of the main circuit at either of the three points a^2 , b^2 or k k^2 will cause the current to traverse over two circuits which are as follows: battery X, conductor C, contacts a^2 , 45 conductor D, wire y^3 , contacts y^2 y' , wire y , conductor D', signal receiving mechanisms or bells F^3 F^4 , conductor D^2 , wire x^5 , spring contacts x^4 x^3 and wire x^2 to battery. The 50 other circuit by which the remaining signals are actuated may be traced from the battery X, conductor C contacts a^2 , conductors D D', signal receiving devices or bells $F' F^2$ and conductor D^2 to battery.

What is claimed is:—

1. In an apparatus of the character described, the combination with a loop circuit provided with a plurality of alarm signal mechanisms arranged in series thereon, a relay coil in said circuit, a source of current 50 supply connected to one end of the loop, and a resistance bridged across the loop and maintaining a closed circuit, of means for short-circuiting said resistance, sets of contacts normally retained in opened condition 5 by current flowing in the relay, and current

supply leads extending to said contacts and from the latter to the other end of the loop circuit.

2. In a fire alarm circuit the combination with two looped conductors, a source of current supply connected to one portion of said loop and alarm devices each connected to the two conductors in different portions of the loop, of a relay interposed in the loop, a resistance coil closing the circuit through 70 the latter and normally rendering the alarm devices inoperative, leads from the source of current attached to a different point of the loop and having contacts therein which are held open by current flowing in the relay 75 coil, and means for rendering the resistance 80 inoperative.

3. The combination with a loop circuit, of a resistance bridged across said circuit, a relay interposed in said loop, a source of current supply in said circuit whereby the relay is maintained energized through the resistance which maintains the circuit normally closed, and contacts under the control of said relay having leads tapped to said 85 circuit whereby, upon the breaking of said circuit, current is fed to the same upon each side of the break.

4. The combination with an alarm circuit, of a source of current supply therein, a high 90 resistance arranged to close said circuit and reduce the flow of current therethrough, a relay maintained energized by the reduced flow of current, through the circuit closed by the resistance aforesaid, and contacts under the control of the relay and connected to the circuit whereby when said relay is deenergized, current will be supplied to the 95 alarm circuit.

5. The combination with a loop circuit, of 100 alarm receiving devices therein, a source of current supply, normally opened contacts for despatching alarm signals arranged to be received on said alarm receiving devices, a relay in said alarm circuit, and means 105 under the control of said relay for supplying current to either side of a break in said alarm circuit.

6. The combination with a loop circuit, of alarm receiving devices therein, a source 110 of current supply, normally opened contacts for despatching alarm signals arranged to be received on said alarm receiving devices, a relay in said alarm circuit, a high resistance for reducing the current flow in said 115 loop circuit to maintain the relay energized, and contacts under the control of the said relay arranged in sets, one contact of each set being connected to one end of the loop circuit and the co-operating contact of each 120 set being connected to the opposite end of the loop circuit.

7. The combination with a loop circuit, of alarm receiving devices therein, a source 125 of current supply, normally opened contacts 130

4
for despatching alarm signals arranged to be received on said alarm receiving devices, a relay in said alarm circuit, a high resistance for reducing the current flow in said 5 loop circuit to maintain the relay energized, contacts under the control of the said relay arranged in sets, one contact of each set being connected to one end of the loop circuit and the coöperating contact of each set 10 being connected to the opposite end of the

loop circuit, and a second group of contacts under the control of said relay for operating a plurality of trouble signals.

In testimony whereof I have affixed my signature in the presence of two witnesses. 15

DAVID G. DEE.
